UNITED STATES PATENT OFFICE

CARL W. HERZOG, OF TOLEDO, OHIO

ROTARY PUMP

Application filed January 5, 1931. Serial No. 506,594.

My invention has for its object to provide an exceedingly simple and efficient rotary pump that may be easily constructed and assembled, and which may be used for subjecting fluid to pressure. The invention provides a rotary conical member that operates to produce displacement of fluid within a cylindrical shell. It particularly provides a conical rotary member coacting in conjunction with a member having a surface tangential to the conical surface of the rotary member, and a partitioning member rotated with the rotary member to form volume changing receiving and ejecting chambers.

The invention may be contained in structures that partake of different forms and which may be varied in their details and still embody the invention. To illustrate a practical application of the invention, I have selected a pump that embodies the invention as an example of the various structures, and the details of such structures, that contain the invention and shall describe the selected structure hereinafter, it being understood that variations may be made and that certain features of my invention may be used to advantage without a corresponding use of other features of the invention, and without departing from the spirit of the invention. The particular structure selected is shown in the accompanying drawings.

Fig. 1 is a perspective view of the pump without the cover plate. Fig. 2 is an end view of the pump. Fig. 3 is a view of a section of a part of the pump taken on the plane of the line 3-3 indicated in Fig. 2. Fig. 4 illustrates a view of a section when the partitioning member is located in the position shown in Fig. 1. Fig. 5 is a view of a section taken on the plane of the line 5-5 indicated in Fig. 4. Fig. 6 is a view of a section of the pump, the pump being provided with ports that differ from the ports shown in connection with the pump illustrated in Figs. 1 to 5. Fig. 7 illustrates a view of a section through the intake port where the pump is used for pumping fluid in which the pump is located, or submerged. Fig. 8 is a view of a section of the intake port where the fluid is drawn from a container.

Fig. 9 illustrates a view of a section through the outlet port of the outlet pump shown in Fig. 6. Fig. 10 illustrates interconnecting outlet passageways of the pump that are also indicated in Figs. 2, 3, and 5.

The pump shown in Fig. 1 has a cylindrical shell 1 in which is located a rotary member 2. Preferably, the rotary member is provided with a cylindrical part 3 which substantially fits the shell 1. The rotary member 2 may be driven by means of the shaft 4 which may be operated by a suitable motor.

The end edge of the shell 1 is inclined to the axis of the rotary member and may be located in, or parallel to, the plane that extends tangential to the conical surface 8 of the rotary member 2. A rotatable plate 9 has an inner surface 10 that is so located as to make contact along the line of the conical surface 8 of the rotary member 2 that extends from the apex of the conical surface 8 to the edge of the conical surface. In the form of construction shown, the rotatable plate 9 is rotatably supported to maintain its tangential relation and to maintain the line of contact in the same position with reference to the shell 1, by means of the cover plate 11 that may be secured to the inclined edge 12 of the shell 1 by means of suitable screw bolts 13. When the plates are secured in position, a chamber 16 is formed within the shell and between the conical surface 8 of the rotary member 2 and the plane surface 10 of the rotatable plate 9, into which the fluid operated upon is drawn and expressed.

In order to subject the fluid to pressure and move it through the chamber 16, a partitioning member 17 is rotated in the chamber 16. The member 17 is connected to the rotary member 2 to produce rotation of the partitioning member 17 and at the same time to divide the chamber 16 into two chambers 18 and 19. The chambers 18 and 19 alternately operate in the rotation of the rotary member to receive or draw the fluid into the chamber 16 and force the fluid from the chamber 16.

Where the partitioning member moves angularly relative to the rotatable plate, as in the form of construction shown in the draw-

ings, the partitioning member 17 has an edge portion 20 that fits in the channel 21 of the plate 9 and to allow for the angular movement of the partitioning member 17, relative to the plate 9, the edge portion 20 is, preferably, formed semi-cylindrical and the recess 21 is likewise formed substantially semi-cylindrical.

The partitioning member 17 may be connected to the rotary member 2 to rotate the partitioning member about the axis of the cone by location of a portion of the partitioning member in a slot 25 formed in the rotary member 2, and the partitioning member 17 may be held in position in the slot 21, formed in the plate 9, by the surfaces of the slot 25. In order to maintain the cylindrical edge 20 of the partitioning member 17 in the slot 21, and yet permit angular movements of the edge 20 during the rotations of the rotary member 2, the partitioning member 17 is, preferably, formed semi-circular and the bottom of the slot 25 is also formed to have a circular bottom 26 having its center at the apex of the conical surface 8. As the rotary member 2 is rotated, the inclined cover plate 11 maintains the rotary plate 9 in a tangential relation along the constant line of contact and as the partitioning member 17 moves, relative to the inclined rotatable plate 9, its edge 20 swings through the angle of inclination of the rotative plate 9 to the axis of the cone as it passes from positions at right angles to the axis to positions extending through, or parallel to, the tangential line of contact along the cone.

The fluid is directed into the shell at a point on one or the other sides of the plane of the tangential line of contact and the axis of the conical surface, depending on the direction of rotation, and is forced out of the shell from a point on the opposite side of the said plane. Thus, in the form of construction shown, the fluid is admitted on a leading side of the tangential line of contact between the rotary member 2 and the rotatable plate 9 that extends from the edge of the cone to its apex, while the fluid is forced from the shell on the following side of the tangential line of contact. Where the pump is submerged in a liquid or is located in a gas, such as in air, a plurality of openings 30 may be formed in the wall of the shell 1 above the edge of the conical surface 8 and, as the partitioning member 17 is rotated, the chamber on the side of the partitioning member that the openings are located on, is enlarged while the other chamber is decreasing in volume and, consequently, the partitioning member forces liquid or gas or air through the port 31, preferably formed near the following side of the tangential line of contact.

The port 31 is formed in the cover plate 11 and a suitable connection may be made therewith. The outlet port 31 may be con-

nected with the chamber 16 by means of a channel 32, formed in the cover plate 11, and the openings 34 formed in the rotatable plate 9. The channel 32 extends arcuately about the center of the plate 9 and is located on one side of the tangential line of contact and its extension across the plate 9, and the openings 34 are located with respect to the apex of the cone so as to move over the arcuate slot 32 to allow the fluid to pass through the recess 32 and the outlet 31 as either of the chambers 18 or 19, between the partitioning member and the tangential line of contact, reduces its volume.

When the edge portion 22 of the edge 20, of the partitioning member, passes through the tangential line of contact, the portion of the chamber 18, between the partitioning plate 17 and the line of contact, is expanded and receives air through the inlets 30, while on the other hand the fluid is being forced from the chamber 19 by reason of approachment of the edge portion 23 of the edge 20 towards the tangential line of contact, the fluid passing out through the opening 34, the channel 32 and the outlet 31.

Thus, in the continued rotation of the rotary member, the chambers 18 and 19 alternately receive fluid and force it from the chamber 16 during each rotation, and there is produced a continuous draft or suction of the fluid into the pump, and a continuous outward pressure of the fluid through the outlet port.

The pump may be provided with inlet and outlet ports located in close proximity to the tangential line of contact between the rotary member 2 and the rotatable plate 9. As shown in Figs. 6 to 9, the inlet and outlet ports may be provided by forming passageways that extend diagonally to points located in proximity to the tangential line of contact. Preferably, the passageways are made triangular in form so as to conform to the space produced at these points between the conical surface 8 of the rotary member 2 and the plane surface 10 of the rotatable plate 9. The outer ends of the passageways may terminate in suitable bosses for connection with a pipe that may communicate with suitable containers, if desired. As shown in the figures, the passageways 35 and 36 are triangular in form, or communicate with the triangular opening 37 located in proximity to the tangential line of contact between the rotary member 2 and the plate 9. If desired, the passageway 35, that forms the inlet passageway of the pump, may connect with an opening formed in the boss 38 which may be threaded, as at 39, for connection with a suitable reservoir from which the fluid is to be drawn. Likewise, the outlet passageway 36 may terminate in a tapered opening formed in the boss 40 which also may be threaded, as at 41, to connect

with a suitable pipe to receive the fluid from the pump.

I claim:

In a pump, a cylindrical shell, a cylindrical member having a conical end part located in the cylindrical shell, the axis of the cylindrical member and the conical part coinciding with the axis of the cylindrical shell, a circular plate located tangentially to the 5 conical part of the cylindrical member and having a groove, the groove having a substantially semi-cylindrical surface, a semi-circular partitioning member extending diametrically across the shell, its diametrical 10 edge portion having substantially a semi-cylindrical surface and adapted to fit the groove of the plate and move angularly within the groove of the said plate, the cylindrical member having a slot extending 15 through the apex of the conical part of the cylindrical member and for receiving the semi-circular partitioning member in the channel, the said plate and shell having an 20 outlet port and means for admitting entrance 25 of air into the interior of the shell at any one of a plurality of points extending substantially over 180 degrees beginning at the point of intersection of the said tangential line with the base of the conical part of 25 the cylindrical member, means for rotating the cylindrical member, and a closure plate for closing the cylindrical shell, the bottom 30 of the slot of the cylindrical member operating to hold the circular plate against the closure plate, and means for rotating the cylindrical member.

In witness whereof I have hereunto signed my name to this specification.

CARL W. HERZOG.
